DISPLAY DEVICE

Ralph J. Mancuso, Brooklyn, N. Y., assignor to
Royal Mounters, Inc., Long Island City, N. Y.,
a corporation of New York

Application January 11, 1936, Serial No. 58,666

15 Claims. (Cl. 211—135)

The present invention relates to display devices, and more particularly to a foldable display for supporting articles of merchandise.

The present invention aims to provide a simple inexpensive foldable device for displaying articles of merchandise which is constructed of a minimum number of parts and which can be quickly assembled in the manufacture thereof. In addition, the display device may be shipped in a flat collapsed position and may be set up into display position by simple folding operations, thereby minimizing the time and skill required in arranging the device.

An object of the present invention is to provide an inexpensive display device which is sturdy in construction and capable of supporting the weight of the articles of merchandise exhibited.

Another object of the invention is to provide an attractive display device for arranging articles of merchandise thereon.

Another object of the invention is to provide a box-like display device having display niches or pockets therein for the merchandise.

Another object of the invention is to provide a display device having article displaying portions at opposite sides thereof.

Another object of the invention is to provide a display device suitable for displaying articles of merchandise either in store windows or on sales counters.

A further object of the invention is to provide a display device which is easily set up and collapsed by simple folding operations and which, when set up in display position, is locked against being collapsed accidentally.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a perspective view illustrating a preferred embodiment of the present invention showing the device arranged in display position;

Fig. 2 is an exploded perspective view of parts of the display device prior to being assembled;

Fig. 3 is a sectional view taken along the line 3—3 of Fig. 1;

Fig. 4 is a sectional view similar to Fig. 3

showing the device in a partially collapsed position;

Fig. 5 is a perspective view, partly in section, illustrating a modified display device having a collapsible display card;

Fig. 6 is a perspective view showing the display card in partially collapsed position; and

Fig. 7 is a sectional view taken along the line 7—7 on Fig. 5, showing the card in fully collapsed position.

Referring again to the drawings, the preferred embodiment of the display device illustrated comprises a foldable or collapsible box-like base or body portion 1 (Fig. 1) having suitable niches, alcoves or display pockets 2 at one side thereof and, if desired, similar niches or the like may be provided at the opposite side thereof. A suitable display card or shield 4 may be mounted on the top of the base and may have suitable decorative or advertising matter thereon. Preferably, the parts of the device are formed of cardboard or other suitable material of any desired thickness which may be decorated, if desired, by color contrast, printing or lithographing. Also, the shape of the device may be in any suitable ornamental form.

The base or body portion may be constructed of a single sheet of material, but preferably comprises a front member 5 having a center panel 6 and end panels 7, and a corresponding back member 9 having a similar center panel 10 and end panels 11. The members 5 and 9 provide the front or back sides of the base and are substantially identical in design and construction to permit them to be used interchangeably, however, for describing the construction of the device more clearly the member 5 will be referred to as the front member and the member 9 will be referred to as the back member. The members 5 and 9 may be foldably connected or attached to each other by foldable strips 12 at the end panels of either the front or back member and preferably the end panels are foldable with respect to the center panels to facilitate collapsing the front and back members in flat position. It will be understood that the base or body may be in any box-like form, other than the hexagonal design illustrated herein. For example, the base may be rectangular or octagonal. The base preferably flares upwardly and outwardly as shown, but may have vertical sides or may be in the shape of a frustum of a pyramid.

In order to provide the niches or pockets the front and back members have cut-out openings 14 at the center panels thereof. These openings

may be provided by stamping out suitable wings, flaps or doors 15, foldably connected to the panel at 16, which may be folded inwardly into the body to provide side walls (Fig. 1) for the niches or pockets. Any number of these pockets may be provided and they may be arranged in vertical alignment as shown or in any other suitable manner. Also, the niches or pockets may be omitted from one side of the cabinet. The free 10 ends of the doors 15 preferably are provided with tabs 17 or the like adapted to fit into suitable slots described hereafter for holding the doors in open position. Also, suitable recesses 19 may be provided to facilitate engaging the doors to 15 fold them.

If desired, the foldable flaps or doors 15 may be omitted by stamping out openings 14 of suitable shape and size. For example, if the flaps or doors are not desired, the opening may be 20 circular, oval or triangular. When the doors are omitted the niches or pockets of the display device are not provided with side walls, so that portions of articles exhibited may project beyond the ends of the shelves 20. When 25 the side walls are omitted, a lighting system may be installed within the display cabinet whereby the illumination may enter from the sides of the pockets and fall upon the objects on the shelves.

30 The bottoms or floors of the pockets at the front side of the display device may be formed from foldable flaps 20 cut from an upright sheet member 21 and may be attached adhesively to the inner side of the center panel 6 adjacent to the openings 14 by foldable strips 22. The sheet member 21 preferably extends vertically downwardly as far as the lower edge of the base so that its lower end 23 rests on the floor or surface where the display is set up and acts as an additional support.

40 When the flaps 20 are cut or stamped from the sheet 21, openings 24 are formed. These openings may be closed by attaching a member 25 to the vertical member 21 at the back side 45 thereof, having vertical portion 26 providing a back wall for the niches or pockets at both sides of the device. The wall portion 26 preferably has slits or slots 27 substantially at the side edges thereof for receiving the tabs 17 of the doors or flaps 15 (Fig. 3). It will be understood that the number of back wall members 25 utilized, corresponds to the number of display 50 pockets and openings 24. Preferably, the members 25 are each provided with a foldable horizontal flap 29 adapted to form the bottom or 55 floor for the niches or pockets at the back side of the display device. The flaps 29 may be adhesively attached to the inner side of the panel 10 adjacent to the openings by suitable foldable 60 strips 30.

In order to close the upper end of the body or base, a cover member 31 is attached to the front and back members 5 and 9. Preferably, the cover member conforms to the contours of the side and 65 end panels so that the closed end is neat in appearance, and is foldably attached to the members 5 and 9 by foldable strips 32. Preferably, the cover is provided with a crease 34 to permit it to be folded upwardly to collapse the body or 70 base portion. Suitable slots or slits 35 are provided in the cover for receiving tabs 36 (Fig. 1) of the display card or shield 4 mounted on the base. The card 4 has legs or flaps 37 adapted to be spread apart to form a support for the 75 card. In Figs. 2, 3 and 4 the card has been

omitted in order to illustrate other details of the invention more clearly and to illustrate that the device may be used either with or without the card.

In the manufacture of the device, the various parts are stamped from sheets of cardboard or other material, are provided with the folding creases and are thereafter folded. The members 5 and 9 are then attached to each other and the back wall members 25 are attached to the reinforcing sheet 21. Thereafter the strips 22 and 30 of the floor portion 20 and 29 respectively, are attached to the inner sides of the members 5 and 9, and to complete the body, the top or cover 31 is attached to the upper ends of the members 15 5 and 9. Preferably, the various parts or members are attached by pasting or gluing them together, but may be assembled with staples or in any other suitable manner.

In shipping the device, the doors or flaps 15 20 of the niches or pockets are folded into the plane of the center panels (Figs. 2 and 4) and the back and front members 4 and 9 are pushed toward each other permitting the cover 31 to fold upwardly and permitting the floors or bottoms 20 and 29 of the niches to fold downwardly. While the body of the display device is shown only partially collapsed in Fig. 4 it will be readily understood that the parts may be further folded in the direction indicated by the arrows, 25 30 until the device is flattened out. The legs 37 of the card 4 may be folded together so that the card may be shipped in flattened or collapsed position. Preferably, the body and card are shipped dismantled to conserve packing space. 35

When it is desired to set up the display device, the end panels of the body are pushed slightly toward each other which causes the front and back members 5 and 9 to move apart and permit the cover 31 to fold downwardly and the 40 floor members 20 and 29 to fold upwardly. The doors or flaps 15 are then folded inwardly into the body and the tabs 17 are inserted into the slots 27. The doors when in this position rest upon the floors of the pocket to reinforce the 45 display against being crushed. Also, the upright sheet member 21 has its lower end 23 resting on the supporting surface for the device to additionally strengthen the device. Thereafter, the 50 display card 4 may be mounted on the cover 31 by inserting the tabs 36 into the slots 35. The display device is then adapted to receive suitable articles of merchandise which may be arranged in the niches or pockets or on the top in any desired manner.

In Figs. 5, 6 and 7 there is shown a modified form of the display device in which the front and side portions of the device may be formed by a member 38 having cut-out flaps 39 at the front forming the openings 14. The flaps may be folded inwardly to provide supporting shelves for articles to be exhibited, and preferably are foldably attached at their free edges to an upright sheet member 21', forming the back wall of the pockets. A suitable back member 40 may be foldably attached to the member 38 at 41 and a suitable foldable top portion 42 may be foldably attached to the upper edges of the member 21', 38 and 40. If desired, a basket portion 44 adapted to retain articles may be provided at the top of the display 70 device.

The back member 40 of the display device preferably has an upwardly extending portion 45 providing means for attaching a display card 46 thereto. The display card 46 may be foldably 75

attached to the display device so that it may be doubled back substantially against the rear of the cabinet to conserve space during shipment of the display devices. To facilitate folding the display card may be provided with a crease or articulation 47 at a point above the upwardly extending portion 45 of the back member.

In order to hold the card upright in the display position, a suitable supporting member 49 is utilized which may have one end portion fastened to the display card at one side of the crease 47, and the other end at the other side of the crease. Preferably, the supporting member 49 has a foldable portion 50 provided by a vertical joint or crease 51 adapted to be turned to a position substantially at right angles to the other portion of the member 49 which is attached to the card. The portion 50 may be held in that position by a suitable foldable wing or ear 52 stamped from the member 49 and having a locking notch 54 thereon adapted to cooperate with a notch 55 in the portion 50. When the wing is in the supporting position, illustrated more particularly in Fig. 5, the flap portion 50 prevents the card from being folded along the crease 47 and serves to hold the card in display position. When the wing or ear is released the flap 50 may be folded against the back of the card and the card may be folded against the back of the device.

The latter operation is accomplished by providing suitable horizontal creases 56, 57 and 59 on the supporting member 49 and the flap 50. The crease 56 is preferably below articulation 47 and substantially adjacent to the attached lower portion of 49, while the crease 59 is above the crease 47 and is substantially adjacent to the attached upper portion of member 49. The crease 57 is positioned between creases 56 and 59 and preferably above horizontal articulation 47 of the card 46. Preferably the distance between the creases 56 and 47 is equal to the distance between creases 57 and 59 and the distance between the creases 56 and 57 is equal to the distance between the creases 47 and 59 so that the display card and the portion of the supporting member between the creases 56 and 57 fold back in parallel relationship. In this manner, the card may be freely folded, but at the same time the joints 50 or creases are in staggered relation to strengthen the supporting device. With this arrangement of parts the card will be held in an erect position by the supporting member, even if the card should be severed along the crease 47.

55 Also, the staggering permits the card to be folded against the rear of the cabinet without interposing a bulky joint of several thicknesses, thereby minimizing the strains on the scored or weakened portions and preventing the parts from tearing along the scored portions. In addition, the separate type of joints provided at different points facilitate the folding of the card to a thin cross-section that occupies small space and prevents undue bulging at the folded portions.

65 It will be seen that the present display device has display niches or compartments at two sides thereby making it very desirable for use on sales counters, since the device presents a pleasing appearance from all sides. The display may also be 70 used for decorating store windows, one side being presented to the store front and the other side being visible from the interior of the store. The device is easily set up and collapsed and can readily be stored or shipped in its flat position. The 75 device is rugged in construction and can with-

stand any rough usage to which it may be subjected. In addition, it is suitable for displaying relatively heavy articles of merchandise.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A display device comprising front and back panels having side portions for foldably connecting said panels, at least one of said panels having a display niche, and means intermediate said front and back panels providing a back wall for the display niche, said means being foldably attached to one of said panels.

2. A display device comprising foldably connected front, back and side panels, said front and back panels having a display pocket, and a member intermediate said front and back panels and foldably attached to one of said panels and providing the back wall of said display pocket.

3. A display device comprising a foldable box structure having an inwardly extending display compartment at one side thereof, a portion of said box structure being cut out to provide foldable flaps for providing side walls for the compartment, and a member foldably attached to said box structure for attaching the flaps thereto.

4. A display device comprising a foldable box structure having a display niche at one side thereof and a second display niche at the opposite side, flaps at the respective sides of said box structure adapted to be folded inwardly to provide side walls for said niches, and a member intermediate the respective sides of said box structure forming the back wall of said niches, said member having means for attaching said flaps thereto.

5. A display device comprising a foldable body structure having a display pocket at one side thereof, a member foldably attached to said body structure providing the bottom and back walls of said pocket, and flaps formed from said body structure adapted to be folded inwardly to provide side walls for said pocket.

6. A display device comprising a collapsible body structure having a display niche at one side thereof, a member foldably attached to said body structure providing the bottom and back walls of said niche, flaps formed from one side of said body structure adapted to be folded inwardly to provide side walls for said niche, and attaching means associated with said flaps and the back wall of said niche.

7. A display device comprising foldable front, back and side panels forming a box structure, one of said panels having a number of display compartments therein, and a member intermediate said front and back panels having a corresponding number of flaps folded out of the plane of said member to provide a bottom for each of said compartments, said flaps being foldably attached to the interior side of said panel having the display compartments therein.

8. A display device comprising a foldable side member having a display niche therein, wings 70 formed from said side member for providing the side walls of said niche, an upright member having a flap molded out of the plane of said member to provide an opening, said flap being foldably attached to the interior of said side 75

member to provide a bottom or floor for said niche, and a member secured to said upright member extending across the opening therein to provide a back wall for said niche.

5. In a display device, the combination of a foldable body structure having a cut-out portion at one side thereof and a similar cut-out portion at the opposite side thereof for providing display niches, a member within said body structure having a flap folded out of the plane thereof to provide an opening in said member, said flap being foldably attached to one side of said body structure to provide a bottom for one of the display niches, and a second member secured to said first member having a portion extending across the opening of said first member to provide a back wall for both of said niches, said second member having a foldable portion attached to the other side of said body structure 10 to provide a bottom for the other of said display niches.

10. In a display device the combination of a collapsible body structure having an opening at one side thereof and an opening at the opposite side thereof for providing display compartments, a member having a flap folded out of the plane thereof to provide an opening in said member, said flap being foldably attached to one side of said body structure to provide a bottom for one 15 of said display compartments, a second member attached to said first member having a portion extending across the opening of said first member to provide a back wall for both of said compartments, said second member having a portion foldably attached to the other side of said body structure to provide a bottom for the other of said display compartments, and flaps at the side of said body structure adjacent said side openings adapted to be folded inwardly to provide side walls for said compartments.

40. 11. In a display device, the combination of a foldable box-like structure having an opening at one side thereof and an opening at the opposite side thereof for providing display niches, an upright member within said structure having a flap folded out of the plane thereof thereby forming an opening, said flap being foldably attached to one side of said structure to provide a bottom for one of the display niches, a second member attached to said upright member having a portion 45 extending across the opening of said first member to provide a back wall for said niches, said second member having a flap portion foldably attached to the other side of said structure to provide a bottom for the other of said display niches, foldable flaps on said sides adjacent said side openings to provide side walls for said niches, and means associated with the side flaps of said structure and said second member for attaching the 50 flaps to said second member.

55. 12. In a display device, the combination of a collapsible body structure having an opening at one side thereof and an opening at the opposite side thereof for providing display niches, a member having a flap folded out of the plane thereof to provide an opening, said flap being foldably attached to one side of said body structure to provide a bottom for one of the display niches, a second member having a portion extending across 60 the opening of said first member to provide a back wall for said niches, said second member having a portion foldably attached to the opposite side of

said body structure to provide a bottom for the other of said display niches, foldable flaps cut from said body at the sides of said body structure at said side openings to provide side walls for said niches, and a foldable cover part attached to the upper end of said body structure.

65. 13. In a display device, the combination of a foldable box-shaped body structure having a plurality of openings at one side thereof and a plurality of openings at the opposite side thereof for providing display compartments, foldable wings formed from the sides of said body structure at said openings to provide side walls for said compartments, an upright member intermediate the sides of said body structure adapted to reinforce said body structure, said upright member having a plurality of cut out foldable flaps corresponding to the number of openings at one side of said body structure, said flaps being foldably attached to one side of said body structure adjacent to said openings to provide bottom portions for said compartments, and members having a portion secured to said upright member and extending across the portions of said upright member where the flaps are cut out, to provide back 70 walls for the compartments at each side of said body structure, said last members having a foldable portion foldably attached to the other side of said body structure adjacent said openings to provide bottom portions for said compartments 75 at the other side of said body structure.

80. 14. In a display device formed of cardboard sheets or the like, the combination of a body member having a center panel and end panels, a second body member having a center panel and end panels, the respective end panels of said body member being foldably attached to each other to provide a collapsible box-like body, each of said center panels having an opening therein for providing a display niche and having flaps adjacent 85 to said openings for providing side walls for said niches, an upright member having a flap portion attached to one of said body members for providing a bottom for the niche in one of said body members, and a member attached to said upright member having an upright portion providing a rear wall for both of the niches and having a flap portion attached to the other of said body members for providing a bottom for the niche in 90 said other body member.

95. 15. In a display device, the combination of a body member having a side portion provided with foldable end portions, a second body member having a side portion provided with foldable end portions, the respective end portions of said body member being attached to each other to provide a foldable body structure, each of said side portion having an opening therein for providing a display pocket and having flaps adjacent to said openings for providing side walls for said pockets, 100 an upright member intermediate said body members having a portion attached to one of said body members for providing a bottom for the pocket in one of said body members, a member attached to said upright member having a portion providing a rear wall for both of the pockets and having a portion attached to the other of said body members for providing a bottom for the pocket in said other body member, and means for attaching said flaps to said last member, a foldable cover part 105 attached to the upper ends of said body members.

RALPH J. MANCUSO.
